Primary Examiner — Tamara L Hahn(74) *Attorney, Agent, or Firm* — Vorys, Sater, Seymour and Pease, LLP; Maryellen Feehery Hank(57) **CLAIM**

The ornamental design for a trash bin, as shown and described.

DESCRIPTION

FIG. 1 is a top, front and left-side isometric view of a trash bin, shown in a closed position;

FIG. 2 is a front view thereof;

FIG. 3 is a back view thereof;

FIG. 4 is a left-side view thereof; the right-side being a mirror image;

FIG. 5 is a top view thereof;

FIG. 6 is a bottom view thereof;

FIG. 7 is a bottom, back, and left-side isometric view thereof; and,

FIG. 8 is a top, front and left-side isometric view of a trash bin, shown in an open position.

The portions shown in white and outlined in broken lines depict portions of the trash can that form no part of the claimed design.

1 Claim, 8 Drawing Sheets(56)
